UNITED STATES PATENT OFFICE.

ROBERT J. LEWERS, OF NEWPORT NEWS, VIRGINIA.

TOILET-DISINFECTOR.

1,117,868.

Specification of Letters Patent.

Patented Nov. 17, 1914.

Application filed September 8, 1914. Serial No. 860,753.

To all whom it may concern:

Be it known that I, ROBERT J. LEWERS, a citizen of the United States, residing at Newport News, Virginia, have invented certain new and useful Improvements in Toilet-Disinfectors, of which the following is a specification.

The present invention relates to toilet disinfectors, and has for its principal object 10 to provide a simple, efficient and economical means for supplying an antiseptic or deodorant to the bowl of a water closet.

A further object consists in so forming and arranging the device as to have it operate in a place, concealed from view, and yet at the same time readily accessible for the purpose of refilling.

With these and other objects in view, the invention consists in the combination and 20 arrangement of parts more fully described in the following specification, illustrated in the accompanying drawings, and pointed out in the appended claims.

In the drawings: Figure 1 is a plan view 25 of a closet seat showing one embodiment of the present invention applied thereto. Fig. 2 is a section taken on the line 2—2 of Fig. 1, looking in the direction of the arrow. Fig. 3 is an enlarged plan view of the appliance detached. Fig. 4 is a transverse section taken on the line 4—4 of Fig. 3. Figs. 5 and 6 are front elevation and plan views respectively of a slightly modified form of the invention.

Referring to the drawing, and particularly to Fig. 1, a water closet seat is shown at 1, hinged at its rear edge as at 2 to the frame work 3. The disinfecting device which forms the subject matter of this application is secured to the underside of the closet seat and appears in this view in dotted lines.

The appliance itself consists of a metal tubular container 4, curved so as to conform 45 with the contour of the rear portion of the seat 1 and secured to the underside thereof by means of screws or alike attaching means 5 which pass through the flat end plates 6. The central portion of the tube is provided 50 with end partitions 7, 7 and forms a reservoir chamber 8 provided with a centrally located inlet opening 9, adapted to be closed

by a stopper or cork 10. At either end of the tube 4 adjacent the partitions 7 are two compartments 11, having perforated walls. 55 One or more wicks 12 are passed through the container 4, through perforations in the partition walls 7 and project sufficiently out of the end chamber 11 to hang down into the bowl or basin of the closet. The filling 60 neck or opening is formed on the inner curved side of the tube 4 so that as the seat is raised the neck assumes a vertical position. The disinfectant or deodorant which is in liquid form is poured into the fountain or reservoir chamber 8. From thence it is absorbed and conducted by the wick 12 to the basin. The end chambers 11 with perforated walls contain cotton packing or gauze upon which the moisture is rapidly 65 evaporated, thus serving to produce fumigating effect on the surrounding air.

Referring to Figs. 5 and 6 the metal tubular container is here shown in a somewhat modified form. The main central part of 75 the tube portion is slightly offset from the plane of the end compartments 11 as shown at 4^a which are secured to the underside of the closet seat, so as to leave a space between the tube proper and the closet seat. The 80 central part is also curved rearwardly as seen in plan view 4^b in Fig. 6 which construction serves as a trap as well as a fountain when the closet seat is raised to its vertical position.

The slow yet steady flow of the disinfectant solution into the basin at all times is very effective and requires no adjusting or regulating devices.

The appliance can be easily attached to 90 any closet seat and once secured in position is readily accessible for filling purposes without necessitating its being removed. Should the device become clogged or in any way stopped up it is only necessary to grasp 95 the end of the wicks 12 and pull them back and forth once or twice.

Having thus described my invention what I claim is:

1. The combination with a water closet 100 having a seat movable in relation to the bowl, of a disinfecting device comprising a tubular container, permanently secured to the underside of said seat and means pass-

ing through the tubular container for conducting a steady flow of the disinfectant to the bowl below, substantially as described.

2. A disinfecting device adapted to be secured to the underside of a water closet seat comprising a curved tubular container, having a central reservoir chamber and adjacent evaporating chamber, a filling neck for said reservoir and a wick passing

through the entire length of the container 10 and having its free ends projecting therefrom, substantially as described.

In testimony whereof, I affix my signature in presence of two witnesses.

ROBERT J. LEWERS.
